C. B. LAWTON.
INSULATING CONSTRUCTION.
APPLICATION FILED JULY 25, 1919.

UNITED STATES PATENT OFFICE.

CHARLES B. LAWTON, OF HUNTINGTON, WEST VIRGINIA.

INSULATING CONSTRUCTION.

1,413,169.

Specification of Letters Patent. Patented Apr. 18, 1922.

Application filed July 25, 1919. Serial No. 313,401.

To all whom it may concern:

Be it known that I, CHARLES B. LAWTON, a citizen of the United States, and a resident of Huntington, in the county of Cabell 5 and State of West Virginia, have invented certain new and useful Improvements in Insulating Constructions, of which the following is a specification.

My invention relates to insulating walls 10 or the like, and more especially refrigerating constructions. Its object is to provide a wall having a large proportion of interior space with a considerable vacuum therein, and with its joints so formed that it will 15 be impervious to the passage of air.

A further object is to construct such a wall of bricks or units of uniform size and shape, respective sides of which will constitute the face of the wall. Further objects will appear 20 in the course of the ensuing description. My invention consists in the improved construction and in the details and arrangement of parts thereof and in the brick or unit as a new and improved article of manufacture, which will hereinafter be more fully 25 described and claimed.

In the drawing:

Fig. 1 is a perspective view of one of the bricks or units embodying my invention, 30 showing the sealed and collapsed end and one of the paneled sides:

Fig. 2 is a similar view of the brick or unit reversed and inverted to show the opposite end and opposite sides:

Fig. 3 is a view corresponding to Fig. 1 but showing a modification;

Fig. 4 is a vertical longitudinal section of part of a wall constructed according to my invention with the use of bricks as shown in 40 Figs. 1 and 2;

Fig. 5 is a vertical cross-section of the same on a plane corresponding to the line 5—5 of Fig. 4;

Fig. 6 is a perspective view of one of the 45 bricks or units of Figs. 1 and 2 after it is blown but with its neck extended and unsealed;

Fig. 7 is a similar view of the same with the neck extended and sealed;

Fig. 8 is a partial vertical longitudinal section similar to Fig. 4 but showing other modifications of bricks or units and showing how their ends are assembled; and

Fig. 9 is a similar view similarly illustrating another modification of the bricks or units.

According to my invention the bricks or construction units are composed of glass or other suitable material having a high degree of ductility when heated to a practical 60 degree.

The use of such material permits the bricks or units to be blown into hollow shape in the same way as bottles are made. This permits these bricks or units to be made with 65 their hollow interiors completely secluded from the atmosphere; so that it is thus possible to have a high degree of vacuum therein by suitably providing for a diminished quantity of air, in the course of the process 70 of sealing the brick or unit.

It is preferable to provide the neck on one of the ends of the brick; and in the preferred construction herein, the end that has the neck is collapsed inwardly of the brick 75 so that there will be no extension of the neck beyond the normal end of the brick.

The collapsing is accomplished more readily if the brick is of symmetrical cross-section.

It is not necessary however, to have such a brick or unit circular in cross-section; and it will be seen that the most practical symmetrical shape is that of an equal-sided rectangle as shown in Figs. 1 and 2. For purposes which will appear in the later description of the construction of a wall or the like with the use of these bricks, it is desirable that the upper and lower sides of the bricks which receive the mortar, cement or the like 90 between the bricks, should be depressed but with a continuous rim therearound. The face sides of the bricks are preferably plain.

It is likewise desirable that both ends of the bricks should be depressed; these have 95 purposes additional to that of depressing one of the ends for retracting the sealed neck.

Answering to these requirements, the brick constructed as shown in Figs. 1 and 2 has a 100 plain front face 1 and a plain rear face 2, the paneled top 3 and the paneled bottom 4, the depressed end 5, comprising the sealed neck 6 retracted therewith inside the normal face of the end of the brick and the opposite 105 end 7 which is also depressed.

The paneled sides 3 and 4 are surrounded by rims composed of the front and rear ribs 8 and 9 respectively and end ribs 10 and 11 respectively.

It is not essential however, that these bricks or units be symmetrical in cross-sec-

tion. They may be wider than high as shown in Fig. 3. Here the construction of the brick is substantially the same as just described with the faces such as the face 1' and the paneled top and bottom as the top 3 with its front and rear ribs 8 and 9. In any of these examples, the tops and bottoms or the ends of the brick are also collapsed, not only in order to provide for the depression 10 thereof to confine the neck 6 inside the normal end surfaces but for the reasons herein-after to be given. Thus, as here shown, these ends have only the upright normal surfaces or ribs 12 and the upper and lower end ribs 13 at the ends of the brick are curved inward along with the respective ends.

The wall 13 is constructed of such bricks as these, very much in the ordinary manner so far as concerns the relative arrangement 20 of the bricks, that is the joints of the successive courses are "broken" as shown in Fig. 4.

However, by this arrangement in conjunction with the depressed or paneled formation of the tops and bottoms and ends of the 25 bricks, practically no exposure of adhesive or binding substances is necessary on the face of the wall in the joints between the bricks.

30 This is accomplished without leaving any crevice continuous through the wall; so that with the proper kind of mortar, cement or other adhesive, the wall may be made completely impervious to the passage of air. This is due to the continuity of the mortar, 35 cement or other adhesive 14 throughout the course from one end to the other as permitted by the ribs 10 and 11 of meeting bricks of one course lying within the depressions of the adjacent tops or bottoms of the next 40 course. Also, where the ends of the bricks are open at the tops and bottoms the adhesive 15 between the ends is continuous with the adhesives 14 in the horizontal joints.

45 This adhesive being continuous entirely around every one of the bricks or units of the wall and being closely adherent to the bricks, it is thus permissible for the ribs 8, 9 and 12 of the adjacent bricks to come against each other, thus forming very closely fitted and well appearing joints.

It is especially desirable on the face of the wall in conjunction with the use of glass or similar bricks having very smooth and well appearing faces.

55 The close contact of all bricks in these parts is clearly seen in Fig. 5. As before said, these bricks are preferably blown into shape; and in the first stages of their manufacture the operation will not materially differ from those in the first stages of manufacturing of bottles.

In fact as seen in Fig. 6, the brick at the completion of these stages when standing on its closed end very much resembles a 65 square paneled bottle with a short neck.

However, the next stage in making these bricks is to seal these necks by melting or welding the material thereof so that the article then appears as shown in Fig. 7. The desired degree of vacuum may be provided either by exhausting most of the air from the interior of the brick while its neck 6 is still open as in Fig. 6 and then sealing the brick while this exhaustion of the air is maintained. Or the brick may have its neck 6 sealed as in Fig. 7 while the entire brick is still comparatively hot and thus has a comparatively small quantity of highly rarefied air in it, which air, contracting upon the final cooling of the brick, leaves a considerable vacuum therein.

In this latter connection it may be said that collapsing of the flat walls of the bricks will not occur, because the contained rarefied air will cool sufficiently to impose on this wall any considerable excess of atmospheric pressure only after the walls themselves have cooled sufficiently to become amply self-sustaining against such excess. The neck 6 of the brick may be left extending as in Fig. 7 90 if the opposite end 7 is depressed sufficiently so that each brick receives in this depressed opposite end 7 the extending neck 6 of the adjacent brick as shown in Fig. 8.

As shown in Fig. 9 if the end 5 having ⁹⁵ the neck 6 is depressed, the opposite end may be left undepressed, as the end 7".

Either of these examples also permits elimination of appearance of the adhesive on the face of the wall, without sacrificing any 100 of the imperviousness of the construction.

While certain constructional details are deemed preferable in connection with my invention, and we have shown and described these rather specifically in elucidating the 10 construction and use of my invention, as is required, I do not wish to be understood as being limited to such precise showing and description, but having thus fully described my invention, what I claim as new and desire to secure by Letters Patent is: 11

pletely embedded in the cement, substantially as set forth and for the purposes specified.

2. An insulating construction comprising an assemblage of hollow glass bricks each of 5 rectangular cross-section with all adjacent surfaces depressed but with the longitudinal edges of their faces in contact, each end of each brick being curved inwardly and having a recess and one of said ends having an outwardly extending neck, a layer between and filling the depressed surfaces of the adjacent bricks and confined thereto 10 away from said edge and embedding said neck, each glass brick having a material degree of vacuum interiorly thereof and said bricks, when so laid as to break joint, each brick having a continuous layer of cement around its sides and ends and between the 15 adjacent bricks and said cement being confined therein and concealed from view on the respective contacting sides and ends, substantially as set forth and for the purposes specified.
- 20 3. An insulating construction comprising an assemblage of hollow glass bricks each of rectangular cross-section with all adjacent

surfaces depressed but with the longitudinal edges of their faces in contact, each end of each brick being curved inwardly and having a recess and one of said ends having an outwardly extending neck, a layer between and filling the depressed surfaces of the adjacent bricks and confined thereto 25 away from said edge and embedding said neck, each glass brick having a material degree of vacuum interiorly thereof and said bricks, when so laid as to break joint, each brick having a continuous layer of cement around its sides and ends and between the 30 adjacent bricks and said cement being confined therein and concealed from view on either side, substantially as and for the purposes set forth.
